UNITED STATES PATENT OFFICE.

HENRY F. NELSON, OF DANVILLE, ILLINOIS.

SHOE AND BLANK THEREFOR.

Application filed October 6, 1924. Serial No. 741,924.

To all whom it may concern:

Be it known that I, HENRY F. NELSON, a citizen of the United States, and resident of Danville, in the county of Vermilion and State of Illinois, have invented certain new and useful Improvements in Shoes and Blanks Therefor, of which the following is a specification.

This invention relates to the construction 10 of the upper of a shoe and has for an object the production of such an upper from only two main pieces of material, the blanks for which may be cut without much loss of material.

Another object of the invention is the construction of a shoe which will eliminate the usual seam at the back of the quarters, and will form the quarters of a single piece.

Further objects will be apparent from 20 the following detailed description and the appended claims.

In the drawings:

Figure 1 is a perspective view of a shoe 25 constructed in accordance with my invention.

Figure 2 is a plan view of the blank which forms the vamp, tongue, and quarters of the shoe.

Figure 3 is a plan view of the blank 30 which forms the quarters of the shoe.

The blank A is cut in the form shown in Figure 2 and forms the vamp 1, side pieces 2 and counter 3. Slits 4 and a partial cross slit 5 form the tongue 10 and a cut 6 separates the two parts of the counter 3. The corners of the upper part of the counter may be rounded as shown at 7 if desired. The outer curved edge 8 is sewed or otherwise fastened to the sole C of the 40 shoe while the rear edges 9 which are slightly inclined, are fastened together at the rear of the heel. The inclination of these edges is intended to conform to the usual form of the foot at the heel and thereby procure a better fit.

The blank B is of the form shown in Figure 3, and is symmetrical on either side of a central line 18. The portions adjacent this line form the quarters 11. An approximately semi-circular portion is cut out at 12 which comes opposite the upper portions 13 of the counter and prevents undue thickness at this point. Slits 14 are made as indicated, and the edges 15 from the cut out 50 12 to the slits 14 are sewed to the edges of the blank A formed by the cuts 4, the edges

15 lying on the inside of the shoe. The short portions 16 of the edge on the outside of the slits 14 lie outside of the shoe as clearly shown in Figure 1. The curved portions 17 of the blank and the portions 22 60 form the top edges of the shoe as indicated.

Double rows of stitching 19 secure the two pieces together along the sides, and the front tabs 21 which lie outside the shoe 65 have an additional row of stitching 20. Instead of rounding the upper corners of the counter as shown at 7, they may be left angular as indicated at 23 in Figure 1, thus avoiding the necessity of rounding the corners. The upper edge may have a strip 24 70 attached to the inside for stiffening, and the usual eyelet holes 25 may be provided if desired.

It will be observed that the two blanks 75 can be readily cut or stamped out of leather with but little waste, and that a well formed shoe can be made with a relatively small amount of stitching. Particularly is it to be noted that the quarters are formed in one 80 piece, obviating the usual back seam in the upper part of the shoe where the greatest number of rips usually occur. Variations may of course be made in the curved portions 17 and 22 of blank B for the purpose 85 of varying the appearance or for fitting the shoes to feet having special characteristics. The form of the tongue may also be varied by trimming the same, but the tongue shown is very efficient and labor is avoided 90 by retaining it in the form illustrated. A very small amount of stitching is necessary compared with usual shoes.

Obviously minor details may be varied 95 without in any way departing from the spirit of the invention which is to be regarded as limited only by the scope of the appended claims.

I claim as my invention:

1. A shoe upper formed of two pieces of 100 material, one comprising the vamp, tongue, sides and counter and having its edges stitched together at the rear and having upward extensions from the counter, and the other forming the quarters and upper part 105 of the shoe and having a cut-out portion which registers substantially with the upward extensions of the counter but is of smaller size, the two pieces being stitched together only along the lower edge of the 110 second piece.

2. A shoe upper formed of two pieces of

material one comprising the vamp, sides, tongue and counter and having its edges stitched together at the rear and also having upward extensions from the counter, 5 and the other forming the quarters and upper part of the shoe and having a cut-out portion which registers substantially with the upward extensions of the counter, but is of smaller size, the two parts being stitched

together only along the lower edge of the 10 second part and the lower edge of the second part lying on the inside of the shoe except for tabs at the front which lie on the outside of the shoe.

In testimony whereof, I have hereunto 15 subscribed my name.

HENRY F. NELSON.
